(57) **CLAIM**

The ornamental design for an insert for fishing float or strike indicator, as shown and described.

DESCRIPTION

FIG. 1 is a perspective view of the invented design for an insert for fishing float or strike indicator.

FIG. 2 is a top view of the design of FIG. 1.

FIG. 3 is a front view of the design of FIG. 1.

FIG. 4 is a rear view of the design of FIG. 1, with the right side view, and left side view of the design being the same as FIG. 4.

FIG. 5 is a side view of the design of FIG. 1, viewed from either of the positions of 135 degrees right or 135 degrees left from the front view of FIG. 1.

FIG. 6 is a bottom view of the design of FIG. 1.

FIG. 7 is a perspective view of another embodiment of the invented design for an insert for fishing float or strike indicator.

FIG. 8 is a top view of the design of FIG. 7.

FIG. 9 is a front view of the design of FIG. 7, with the rear view, right side view, and left side view of the insert being the same as FIG. 4.

FIG. 10 is a side view of the design of FIG. 7, viewed from either of the positions of 135 degrees right or 135 degrees left from the front view of FIG. 7; and,

FIG. 11 is a bottom view of the design of FIG. 7.

The broken line areas of the figures show environmental matter and form no part of the claimed design.
